Primary Examiner—Dominic Simone*(74) Attorney, Agent, or Firm*—D. Michael Burns(57) **CLAIM**

The ornamental design for a golf shoe upper, as shown and described.

DESCRIPTION

FIG. 1 is a top perspective view of a golf shoe upper showing our new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof; and,

FIG. 7 is a left side elevational view thereof.

The broken line in FIGS. 1-7 showing a shoe outsole, including cleats, represents the portions of the design that form no part of the claim.
